(57) **CLAIM**

The ornamental design for a pair of shoes, as shown and described.

DESCRIPTION

FIG. 1 is a perspective view of a pair of shoes, showing my design.

FIG. 2 is a front elevation view thereof.

FIG. 3 is a rear elevation view thereof.

FIG. 4 is a left side elevation thereof.

FIG. 5 is a right side elevation thereof.

FIG. 6 is a top plan view thereof; and,

FIG. 7 is a bottom plan view thereof.

The drawings show a left shoe of the pair of shoes. A right shoe is also claimed and is a mirror image of the left shoe shown.

The broken lines in the drawings depict environmental structure and boundaries and form no part of the claimed design.
